UNITED STATES PATENT OFFICE.

CHARLES E. BURCH, OF PALACIOS, TEXAS.

NON-REFILLABLE BOTTLE.

1,196,841.

Specification of Letters Patent. Patented Sept. 5, 1916.

Application filed February 12, 1916. Serial No. 77,994.

To all whom it may concern:

Be it known that I, CHARLES E. BURCH, a native born citizen of the United States, residing at Palacios, in the county of Mata-
5 gorda and State of Texas, have invented certain new and useful Improvements in Non-Refillable Bottles; and I do hereby declare the following to be a full, clear, and exact description of the invention, such as

10 will enable others skilled in the art to which it appertains to make and use the same, reference being had to the accompanying drawings, and to the letters and figures of reference marked thereon, which form a
15 part of this specification.

This invention relates to new and useful improvements in non-refillable bottles, jugs and other containers of like character and consists of a simple and efficient device of
20 this nature so arranged that it will be necessary, when sealed, to destroy the bottle or other retainer, for the use for which it was prepared, as to prevent refilling before access may be had to its contents.

25 My invention is illustrated in the accompanying drawings, in which:

Figure 1 is a central vertical sectional view through the neck of a bottle showing the application of my invention thereto.
30 Fig. 2 is a plan view of a resilient locking ring forming a part of the invention, and Figs. 3 and 4 are detail views showing modifications of the locking rings.

Reference now being had to the details
35 of the drawings by letter, A designates the neck of a bottle having an annular groove B formed therein at any suitable location.

D is a disk with an annular groove E in the circumference thereof and adapted
40 to receive a resilient split ring E, having projecting lugs H thereon, which in the drawings are shown as projecting inwardly, and spaced apart, said lugs being concaved upon their inner edges. Said split ring is
45 adapted to be inserted in the annular

groove of the disk D when the same is inserted in the neck of a bottle and, when said ring and lugs thereon come opposite the annular groove in the neck, it will spring into the annular groove of the neck, 50 while the lugs extend within the annular groove E, thus locking the disk, the stopper or cork E being first inserted in the bottle before the disk is adjusted in place.

When it is desired to dispense the contents of the bottle, the neck of the latter may be cut with a glass cutter about its circumference around the wall of the annular groove in the neck, thus making it easy to break off the top of the bottle to release 60 the ring and disk, after which the cork or stopper may be removed.

It will be at once evident that the construction described is subject to certain modifications without departing from the 65 spirit of the invention, as for instance if the lugs are made very short or narrow, so as to permit the use of a large number on the ring, it might not be required that they should be concaved on the outside if 70 used outwardly.

What I claim to be new is:—

A non-refillable bottle having a neck with an annular groove in its inner face, a disk with an annular groove therein adapted to 75 register with the groove in the neck, a resilient split ring having inwardly projecting portions thereon, spaced apart with their opposite faces flush with the edges of the ring and designed to engage the registering grooves in the neck of the bottle and said disk, and a cork held within the neck by said disk.

In testimony whereof I hereunto affix my signature in presence of two witnesses.

CHARLES E. BURCH.

Witnesses:

NANNIE D. BURCH,
MABEL BURCH.
